RUPTURE PAD

Florencio J. Mendez, New York, N. Y.

Application December 16, 1931
Serial No. 581,428

4 Claims. (Cl. 128—117)

The invention relates to surgical or therapeutic devices, particularly to trusses for the alleviation and cure of abdominal rupture, and has for its general object the provision of a novel pad 5 adapted to form part of a truss and intended to be so located with respect to a rupture as to exert the desired and proper pressure thereupon for the purpose of maintaining and retaining in place the intestine or portion thereof tending to 10 protrude through the abdominal wall or peritoneum.

An important object of the invention is to provide a rupture pad of this character which has its major portion constructed of spongy material 15 and enclosing a relatively hard spring pressed member which is provided for the purpose of exerting the desirable and in fact necessary pressure upon the exact location where the use of the pad is needed.

Another object of the invention is to provide a pad of this character embodying a relatively fixed or stationary member and a detachable pad element connected therewith in a manner which will permit ready and easy disconnection for 25 cleansing purposes or in case replacement is necessary.

An additional object is to provide a device of this character which will be very simple and inexpensive to make, easy to apply, assemble and 30 use, positive in action, efficient and durable in service, and a general improvement in the art.

With the above and other objects and advantages in view, the invention preferably consists in the details of construction and the arrangement and combination of parts to be hereinafter 35 more fully described and claimed, and illustrated in the accompanying drawing, in which

Figure 1 is a side elevation illustrating one 40 form of the invention.

Figure 2 is a rear elevation thereof.

Figure 3 is a longitudinal section taken on the line 3—3 of Figure 2, and

Figure 4 is a view somewhat similar to Figure 3 45 but illustrating a modification and disclosing the two sections of the device disconnected.

Referring more particularly to the drawing, I have shown the device as comprising a cup 10 of metal, hard rubber or in fact any other suitable 50 rigid material slotted at 11 for engagement upon a spring band or other equivalent element of a truss, this member 10 being moreover provided with a stirrup 12 for connection with a strap, web or other securing member. Details such as 55 this really do not enter into the essence of the

invention but are mentioned simply for the sake of clearness.

In the preferred form of the invention the outstanding flange portion 13 of this rigid member 10 is represented as internally threaded for detachable engagement therein and therewith of a shell 14 likewise of rigid material, for instance metal, hard rubber or the like, which carries the pad itself indicated as a whole by the numeral 15. This pad may conveniently consist at least 60 for the major part of sponge rubber indicated at 16, this pad being relatively large, and in fact greater in diameter than the main member 10 so as to protrude or project beyond the edges thereof. This pad 16 has a constricted attaching portion 17 which may be of the same material as the major portion or which may be treated by vulcanization or otherwise so as to be considerably 65 harder. It is also conceivable that it may be a simple expedient to compress this reduced attaching portion 17 of the pad where it is confined within the shell 14. This and other possible variations will at once suggest themselves to one familiar with surgical devices of this character.

A very important feature is the provision 70 within the confines of the reduced or neck portion 17 of the pad of a pressure applying means here disclosed as comprising a partially spherical auxiliary pad member or pressure applying member 18 which may possibly be formed of 75 leather or the like covered with fabric, wire mesh or other similar material indicated at 19 located at the convex side and similarly covered at the plane or flat side by a disk 20 of suitable material constituting an abutment for a plurality of 80 coil springs 21 which have their other ends abutting against a disk 22 bearing against the inner surface of the shell 14 as clearly indicated in Figure 3. Within the pad 16 there is consequently 85 formed a relatively large space or chamber 23 which is filled with air and as this air cannot escape it provides an air cushion which cooperating with the spongy nature of the pad 16 itself 90 will insure, especially by virtue of the springs 21, the application of a sufficiently resilient pressure 95 to the protruding intestine that comfort will result from the device.

Regardless of what exact material may be used for the construction of the major portion of the pad 16 it is intended that the material for the inner pad 18 be relatively hard so that the 100 springs 21 reacting against the disk 22 and the disk 20 bearing against the pad 18 will act to concentrate the pressure to a desirable extent.

In the form of the invention disclosed in Fig- 110

- ure 4, the construction is in all essential respects the same as above described, the only difference being that the exteriorly threaded shell 14 is replaced by a smooth shell 24 provided with lugs 25 located at preferably diametrically opposite points adapted to be received within bayonet slots 26 in a shell 27 corresponding to the member 10 but differing therefrom only in having a smooth interior surface instead of being threaded.
- 10 The pad is of course used in identically the same manner as any other rupture pad forming part of a truss for patients suffering from this infirmity. However, attention is directed to the fact that if a spongy material be used for the main 15 pad 16 such spongy material on account of containing a large number of air cells will be very yielding in character and will be capable of transmitting the pressure exerted by the relatively hard central pad 18 without causing any discomfort or objectionable direct pressure. Owing to the nature of the materials used and the detachability of the elements or various members which constitute the component parts it is apparent that the device may be readily cleansed whenever 20 the occasion may arise. Moreover in case of wearing out of the pads disclosed in either form of the invention it is easily possible to provide renewals without undue trouble or expense. It is really believed from the foregoing that the construction, operation and advantages will be readily apparent to one skilled in the art without further explanation.
- While I have shown and described the preferred embodiment of the invention, it should be understood that I reserve the right to make all such changes in the details of construction as well as in the arrangement and combination of parts as will not depart from the spirit of the invention or the scope of the subjoined claims.
- 46 Having thus described the invention, I claim:
1. A truss pad of the character described comprising a main member of rigid material adapted for mounting upon a truss and including a flanged circular body, a shell member detachably engaged 45 therein, a pad mounted within said shell member and including a spongy main portion projecting therebeyond and provided with a central cavity, a relatively hard pad located within said cavity for exerting an outward pressure upon said first 50 named pad, and spring means reacting against said shell member and against said second named pad.
2. A truss pad comprising an outer member of shell like form adapted for mounting upon a truss, a shell detachably mounted within said outer member, a pad including a major portion of relatively spongy material having a constricted neck portion engaged within said second named shell and formed with a centrally located cavity opening out to that side engaged within the second named shell, a relatively hard pad having a spherical outer face located within the cavity and having a plane abutment disk confronting the second named shell, and springs abutting against said shell and said disk for transmitting pressure through the major portion of the first named pad.
3. A truss pad of the character described comprising a relatively rigid outer member adapted for mounting upon a truss, a shell member detachably engaged within said outer rigid member, a pad including a major portion of relatively spongy rubber containing air cells and of greater diameter than said shell member and formed with a compressed portion secured within said shell member, said pad having a cavity therein leading out to the side thereof engaged within the shell member, a relatively hard pad element located within said cavity and having a spherical face for transmitting pressure through the spongy portion of said main pad, a disk located against the inner face of said relatively hard pad, and a plurality of helical springs reacting against said shell member and said disk for transmitting forces through the spongy portion of the pad.
4. A truss pad comprising an outer member adapted for engagement upon a truss, a shell member detachably engaged within said outer member, a sponge rubber pad having a constricted densified neck portion compressingly engaged within said shell member, said pad having a cavity at its side toward the shell member, a relatively hard pad located within the inner end of the cavity and including an abutment disk, a second disk located at the entrance to said cavity and forming a closure therefor whereby the cavity will constitute a closed air chamber, and a plurality of springs located within the cavity and abutting against said disks.
